UNITED STATES PATENT OFFICE.

GEORGE E. MESECAR, OF SIERRA MADRE, CALIFORNIA.

FENCE-POST.

1,239,120.

Specification of Letters Patent. Patented Sept. 4, 1917.

Application filed September 26, 1916. Serial No. 123,443.

To all whom it may concern:

Be it known that I, GEORGE E. MESECAR, a citizen of the United States, residing at Sierra Madre, in the county of Los Angeles 5 and State of California, have invented a new and useful Improvement in Fence-Posts, of which the following is a specification.

My invention relates to fence posts and 10 has for its object the provision of a metallic post for use in connection with wire fences and capable of holding the wires of the fence thereon at regular intervals.

A further object is to provide means 15 whereby the fence wires may be readily inserted in suitable apertures provided on the posts and thereafter locked firmly in position.

A further object is to provide a post 20 which may be driven into the ground in readiness to receive the fence wires and means removably attachable thereto for clamping the wires in position. Other objects may appear as the description progresses.

Referring to the drawings, Figure 1 is a perspective view of my improved post, broken away at the bottom showing the method of holding the fence wires thereon. 30 Fig. 2 is a fragmentary elevation of the post and the locking member held therein. Fig. 3 is a side elevation of Fig. 2 in position for use, partly broken away at points to show the interior of the post. Fig. 4 is a transverse sectional plan on a plane between the wire holding means.

Similar characters of reference are employed in the several views of the drawing and throughout the specification for indicating like parts.

My fence post comprises only two parts, the outer semi-cylindrical metallic shell 1 forming the post proper, constructed of a single piece of relatively thick sheet metal. 45 An aperture 2 is formed between the edges of the flanges 3 which parallel a line cutting the axis of the post at right angles to the fence and extend substantially outward from the diametrical line paralleling the 50 fence, coincident with which line, the metal forming the post is bent at right angles to the flanges 3 so as to form shoulders 4 on both sides of the aperture 2.

The posts 1 may be set in position and 55 driven into the ground for a sufficient depth by placing a block of wood or a suitable

metal cap of any suitable character over the top of the post, the flanged and recessed side of the post being placed at right angles to the fence line. The outwardly extended 60 flanges 3 which extend the full length of the post are provided with a plurality of upwardly inclined notches 5 which are wider at the edges of the flanges than the inner ends and are arranged, preferably at 65 angles of about 45 degrees. These notches may be provided with smooth edges as shown in Fig. 1, or they may be serrated on the upper edges as shown in Fig. 3, the serrations serving to better hold the wires in 70 the notches.

The fence wires 6 are inserted in the notches 5, and the variation in the width of the notches will accommodate different gages of wire. I provide a locking means 75 for clamping the wires 6 firmly to the posts 1 which includes an elongated member 7 of T formation, which may be formed of a single piece of sheet metal, as shown in the drawings or a piece of standard T iron may 80 be used if desirable. The member 7 extends upwardly from the ground to a point slightly below the top of the post 1 when it is inserted in operating position in the post and the webs 8 thereof are adapted to engage 85 the vertical shoulders 4 and are substantially of the same width as the interior of the post 1 in the plane of the shoulders. The central flange 9 of the member 7 corresponds in width to that of the flanges 3 and 90 extends outwardly from the center of the post into the aperture 2. Downwardly inclined notches 10 which are similar to the notches 5 in the flanges 3 and are similarly spaced, are formed in the flange 9 of the 95 member 7 and are adapted to receive the wires 6 and hold the same therein.

Fig. 3 illustrates the relative positions of the notches 5 in the flanges 3 and 10 in the flange 9 when the wires are taut. When 100 the posts are properly set and driven and the wires 6 inserted in the notches 5 of the posts, the locking member 7 may be inserted in the recess 11 of the posts 1 and the notches 10 in this member hooked over the 105 wires. With the wires 6 held taut by a suitable stretcher, the member 7 may be driven downwardly in the post until the inner ends of the notches are slightly below the inner ends of the notches 5 in the post. A short 110 piece of wire 12 may then be inserted in suitable perforations in the flanges 3 above

the end of the member 7 so as to hold the member 7 in the position to which it has been driven, thus holding all of the wires 6 taut. The ends of the retaining pin or 5 wire 12 may then be bent so that it may not be accidentally removed from the post.

It will be observed that all of the fence wires are thus locked to the post by the single member 7 and at a single operation, thus 10 facilitating the construction of the fence, but if desirable the member 7 may be composed of a plurality of short lengths, as shown in Fig. 3, so that one wire may be strung at a time and locked to the post. In 15 such case the fence wires would not be clamped until all of the wires were in position when the upper section of the member 7 would be driven against the lower sections and then locked downwardly by means of 20 the pin 12.

As long as the pin 12 retains its position over the upper end of the member 7 it will be impossible to remove the wires 6 from the posts, but the manner of clamping the wires 25 to the posts will readily permit the expansion and contraction of the wires by changes in the temperature and such expansion and contraction will be distributed along the line of the fence rather than in 30 the separate bays of the fence, thus preventing unsightly sagging of the wires. As hereinbefore stated the serrated form of 35 notches shown in Fig. 3 may be at times preferable to the smooth edged notches for the serrations will prevent any slippage of the wires in the notches.

The recessed form of post readily permits the driving of the posts into the ground and obviates the necessity for digging post 40 holes, as in the usual cases; and when so driven, inasmuch as the necessity for removing the dirt from the vicinity of the posts will be dispensed with, the posts will be more rigidly and firmly held in position.

Copies of this patent may be obtained for five cents each, by addressing the "Commissioner of Patents, Washington, D. C."

Having thus described my invention, what 45 I claim is:

1. A sheet metal fence post comprising a recessed outer member having diametrically opposite shoulders extending the entire length thereof, a longitudinal opening between said shoulders and a flange on each side of said opening at right angles to said shoulders, said flanges having diagonally disposed notches formed at intervals therein; and an inner member having a web engaging said shoulders and a flange extending at right angles therefrom intermediate of the flanges on said outer member and provided with a plurality of diagonal notches for registration with and disposed 55 in planes substantially at right angles to the notches in said outer member for receiving and holding the fence wires; and means for locking said inner and outer members together.

2. A sheet metal fence post comprising a semi-cylindrical outer member having diametrically opposite shoulders extending the entire length thereof, a longitudinal opening between said shoulders and a flange on each 70 side of said opening extending at right angles to said shoulders, said flanges having diagonally disposed notches formed at intervals therein; and a sectional inner member having a web engaging said shoulders and a flange extended at right angles therefrom intermediate of the flanges on said outer member and provided with a plurality 75 of diagonal notches for registration with and disposed in planes substantially at right 80 angles to the notches in said outer member for receiving and holding the fence wires; and means for locking said inner and outer members together.

GEORGE E. MESECAR.
